CLAIM

The ornamental design for an USB flash disk, as shown and described.

DESCRIPTION

FIG. 1 is a first perspective view of a USB flash disk, showing my design.

FIG. 2 is a second perspective view of the USB flash disk.

FIG. 3 is a front elevation view of the USB flash disk.

FIG. 4 is a rear elevation view of the USB flash disk.

FIG. 5 is a left side elevation view of the USB flash disk.

FIG. 6 is a right side elevation view of the USB flash disk.

FIG. 7 is a top plan view of the USB flash disk.

FIG. 8 is a bottom plan view of the USB flash disk.

FIG. 9 is a perspective view of the USB flash disk in an environment in which it may be used; and,

FIG. 10 is an enlarged view of the design features contained within circle 10 of FIG. 1. The broken lines are environmental structure and form no part of the claimed design.
